[57] CLAIM

The ornamental design for a multihem-height skirt, as shown and described.

DESCRIPTION

FIG. 1 is a bottom plan view of a multihem-height skirt showing my new design;

FIG. 2 is a top plan view;

FIG. 3 is a front elevational view;

FIG. 4 is a left side elevational view, the right side being a mirror image thereof; and

FIG. 5 is a rear elevational view.
